UNITED STATES PATENT OFFICE.

NATHAN M. STONE, OF CHICAGO, ILLINOIS.

ATTACHMENT FOR TELEPHONES AND THE LIKE.

1,324,283.

Specification of Letters Patent.

Patented Dec. 9, 1919.

Application filed October 19, 1915. Serial No. 56,728.

To all whom it may concern:

Be it known that I, NATHAN M. STONE, a citizen of the United States, and a resident of the city of Chicago, county of 5 Cook, and State of Illinois, have invented certain new and useful Improvements in Attachments for Telephones and the like, of which the following is a specification.

My invention relates to improvements in 10 attachments for telephones and the like, and has for its object the provision of an improved construction of this character especially adapted for use in conjunction with telephones and provided with convenient 15 means for retaining various memoranda.

The invention consists in the combinations and arrangements of parts herein-after described and claimed.

The invention will be best understood by 20 reference to the accompanying drawing forming a part of this specification, and in which,

Figure 1 is a perspective view of an attachment embodying my invention, shown 25 in position of use, and

Fig. 2, a different perspective view showing the same in partly opened condition, with portions broken away for the sake of clearness.

The attachment is especially designed for 30 use in conjunction with desk telephones, although it is capable of other uses. In the form shown in the drawing, the attachment is secured to the stem 1 of an ordinary desk 35 telephone by means of a clamp 2 provided with clamping screws 3, said clamp being secured to the under side of a supporting plate 4. The supporting plate 4 is arranged to support a plurality of index cards 5 and

40 is hinged at one end 6 to another supporting plate 7 arranged above the same and adapted to support a memorandum pad 8. The index cards 5 are mounted in position by means of two rings 9, each of said rings 45 passing through a circular opening 9^a and an elongated slot 10^a in plate 4, as best indicated centrally in Fig. 2. Slots 10 are also provided in plate 7 in position to register with and receive rings 9 to accommodate

50 said rings and permit folding of the parts into compact form, as indicated in Fig. 1. Ears 11 are struck up from plate 7 and a

pivot rod 12 mounted therein, said pivot rod serving as trunnions for a clamping member 13. The clamping member 13 is 55 provided with a central recess in its upper face and with upstanding ears 14 co-operating therewith to form a pencil or pen rest, as will be readily understood. The clamping member 13 is also provided with rearwardly extending ears 15 bent about rod 12 to effect a hinge connection therewith. Clamping member 13 is also provided with an upstanding flange 16 at its rear extremity by means of which the same may be readily 65 manipulated, and a spring 17 is provided on rod 12 arranged to hold the clamping member normally in closed position with its clamping edge 18 contacting with and clamping the memorandum pad 8, as indicated. 70

The device is designed to permit of the entering of telephone exchange numbers on the cards 16 and properly indexing the same and also to permit the ready making of 75 memoranda from messages received over the telephone or otherwise. The construction disclosed will be found to be a simple and efficient one for the purpose.

While I have illustrated and described 80 the preferred form of construction for carrying my invention into effect, this is capable of variation and modification without departing from the spirit of the invention. I, therefore, do not wish to be limited to 85 the precise details of construction set forth, but desire to avail myself of such variations and modifications as come within the scope of the appended claims.

Having described my invention what I 90 claim as new and desire to secure by Letters Patent is:

1. A device of the class described, comprising a plate having sets of perforations extending therethrough, each set of perforations consisting of an opening and an elongated slot alining therewith; rings mounted in said sets of perforations; and cards loosely mounted on said rings, substantially as described. 95

2. A device of the class described, comprising a lower plate having sets of perforations extending therethrough, each set of perforations consisting of an opening and 100

an elongated slot alining therewith; rings mounted in said sets of perforations; cards loosely mounted on said rings; and an upper plate hinged to said lower plate and provided with slots adapted to accommodate said rings, substantially as described.

5 In testimony whereof I have signed my

name to this specification in the presence of two subscribing witnesses.

NATHAN M. STONE.
